STATEMENT LIFTER FOR LEDGER TRAYS

Albert K. Kekoa, Honolulu, Territory of Hawaii

Application July 11, 1934, Serial No. 734,668

5 Claims. (Cl. 129—1)

This invention relates to a lifting device for the cards or statements of ledger trays, such as used in banks and the like, the general object of the invention being to provide means whereby all 5 the cards or statements of a tray can be lifted simultaneously and held in lifted position so that another tray can be placed under them to permit the statements to be lowered thereinto, after which the statements can be handled in the usual manner.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a side view of portions of a tray showing the invention in use thereon.

Figure 2 is an end view of Figure 1.

Figure 3 is a section on line 3—3 of Figure 1.

Figure 4 is a view similar to Figure 3 but showing the means for supporting a post at the other side of the tray.

Figure 5 is a section on line 5—5 of Figure 1.

Figure 6 is a section on line 6—6 of Figure 1.

Figure 7 is a top plan view of one of the caps.

Figure 8 is a view of one of the sleeves and its arms supporting member.

Figure 9 is a view of the arm or rod which is supported by the sleeve.

Figure 10 is a view of the staple or double pin used for holding the tray in raised position.

Figure 11 is a sectional view showing how the rod passes through the ledger sheets.

Figure 12 is a fragmentary elevation, with parts in section, showing how the working tray is supported from the device.

Figure 13 is a top plan view of the working tray.

Figure 14 is a section on the line 14—14 of Figure 13.

Figure 15 is a section on the line 15—15 of Figure 13.

Figure 16 is a view of one of the statements or cards.

Figure 17 is a view of one of the ledger sheets to be used with the device.

In these drawings, the ledger tray is shown at A and a plurality of posts 1 is connected to one side of the tray and a plurality of posts 2 to the

other side thereof. Each post has a forked lower end with the outer prong longer than the inner prong, these prongs fitting over the upper part of the tray, as shown in Figures 3 and 4, and a clamp screw 3 passing through each long prong clamps the post to the tray. Each of the posts 2 has an elongated longitudinally extending slot 4 therein which passes through the top of the post and a cap plate 5 is fastened to the post 2 by the screws 6 and covers the upper end of the 10 slot. A vertically arranged eye member 7 is carried by each cap and an eye 8 is formed at the upper end of each post 1 and cross rods 9 pass through the eyes of the two sets of posts and are held in place by the clamp screws 10, these 15 rods acting to brace the posts.

Each slot 4 has its middle portion wider than its side portions and the inner side wall of the wide part is formed with teeth 11 to provide a rack. A shaft 12 passes horizontally through the 20 slots 4 of the posts 2 and has keyed thereto a plurality of pinions 13, one for each post 2. These pinions engage the racks so that rotary movement of the shaft will cause it to move bodily upward or downward in accordance with the 25 direction of rotation of the shaft, one end of which has fastened thereto a crank handle 14.

A plurality of sleeves 15 is slidably and rotatably arranged on the shaft and each sleeve carries an upright member 16 provided with an eye 17, the 30 upper part of each upright member being internally threaded to receive a clamp screw 18. A rod or arm 19 passes through each eye 17 and is adjustably held in place by the screw 18. The rod has an eye 20 at its inner end through which passes a long rod 21, this rod 21 passing through the slots 22 formed in the tabs 23 of the cards or statements 24, shown in Figure 16. As shown in this Figure 16 the ends of each slot 22 are rounded to facilitate the passing of the rod 21 therethrough and by providing the slots 22 these rods can readily be passed through the same even though the statement is located in the tray either to the right or left. As will be seen in Figure 16 40 the tab is placed at the upper end of that part of the statement which is to the left of the line 24' on which the statement is to be cut off. This line may be a perforated line if desired to facilitate removal of the tab carrying part.

A plurality of grooved rollers 25 are rotatably arranged on the shaft 12, the grooves of which receive the walls of the narrow parts of the slots 4 as shown more particularly in Figure 6. These rollers act to guide the shaft in its upward and 55

downward movement to prevent binding of the parts.

The receiving tray is shown in Figures 12, 13, 14 and 15 and it comprises a base 26 having a longitudinally extending undercut groove 27 therein for receiving the dove-tailed lower ends of the posts 28 slidably arranged on the base and carrying the end members 29 which are hingedly connected to the posts by hinges 30. A compression spring 31 connects the lower part of each end member 29 with a lower part of a post 28. The lower edge of each member 29 is provided with an extension bent at right angles, as shown at 32 to bear against the bottom of the groove 27. Eyes 33 are formed at the ends of the base 26 for receiving the eyes of the rods 34 which have hooks at their upper ends for engaging over the bars 3, as shown in Figure 12, so as to support the receiving tray under the statements, after the statements have been raised from out of the main tray.

Figure 17 shows a ledger sheet 35 which is used with this invention, this sheet having a slotted tab 36 at its lower end for receiving the rod 37 at the bottom of the main tray, see Figure 11, so as to hold these sheets in place while the statements are being raised out of the main tray A.

When the statements are to be removed from the tray A it is simply necessary to rotate the shaft 12 by its handle 14 and as this is done the pinions 13 engaging the racks 11 will cause the shaft to move upwardly, carrying the sleeves 15 with it and, through means of the rods 19 the rod 24 will be raised and thus the statements will be lifted out of the tray A. When the shaft 12 reaches a point adjacent the upper ends of the slots 4 the staples 38, shown in Figure 19, are placed in the holes 39 formed in the upper ends of the posts 2 to support the parts in raised position. Then the upper hooked ends of the rods 34 are hooked over the end rods 3 to support the working or receiving tray 26 under the statements, as shown in Figure 12. Then the shaft 12 is lowered sufficiently to deposit the statements into the working tray. Then the end supports 29 of the working tray are moved inwardly to keep the statements as close as possible. Then the bar 24 is pulled out and the statements are ready to be picked up by hand in sections at a time and placed on a desk or table nearby.

This invention will save time and labor and will enable statements to be quickly gotten out and sent to the customers and it will greatly reduce the mental and physical strain on the bookkeeper.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. In combination with a tray for containing cards or statements, a row of posts connected to one side of the tray and having vertically arranged racks thereon, a horizontally arranged shaft, pinions on the shaft engaging the racks, means for rotating the shaft, a rod for passing

through the cards or statements, arms connected to the rod and means for supporting the arms from the shaft.

2. In combination with a tray for containing cards or statements, a row of posts connected to one side of the tray, each post having a longitudinally extending slot therein, one wall of which is formed with teeth providing a rack, a horizontally arranged shaft passing through the slots, pinions carried by the shaft and engaging the racks, sleeves carried by the shaft and having upright parts thereon provided with eyes, rods passing through the eyes, means for clamping the rods in the eyes, a second rod carried by the last-mentioned rods for passing through the cards or statements and means for rotating the shaft.

3. In combination with a tray for containing cards or statements, two rows of posts connected with the sides of the tray, the posts of one row having longitudinally extended slots therein, one side wall of each slot having teeth thereon forming a rack, a horizontally arranged shaft passing through the slots, pinions carried by the shaft and engaging the racks, sleeves carried by the shaft and having upright parts thereon each provided with an eye, a rod passing through each eye, means for clamping the rod in the eye, said rods having eyes at their inner ends, a long rod passing through the last-mentioned eyes and adapted to pass through the cards or statements, means for rotating the shaft, and cross bars connecting the upper ends of the posts at one side of the tray to the upper ends of the posts at the other side of the tray.

4. In combination with a tray for containing cards or statements, two rows of posts connected with the sides of the tray, the posts of one row having longitudinally extending slots therein, one side wall of each slot having teeth thereon forming a rack, a horizontally arranged shaft passing through the slots, pinions carried by the shaft and engaging the racks, sleeves carried by the shaft and having upright parts thereon each provided with an eye, a rod passing through each eye, means for clamping the rod in the eye, said rods having eyes at their inner ends, a long rod passing through the last-mentioned eyes and adapted to pass through the cards or statements, means for rotating the shaft, and cross bars connecting the upper ends of the posts at one side of the tray to the upper ends of the posts at the other side of the tray, a receiving tray including a base and adjustable end members, and hook members carried by the receiving tray, said hook members having hooks adapted to be placed over the end cross bars to support the receiving tray under the raised cards or statements whereby by removing the long rod the statements or cards can be deposited in the receiving tray, and means for holding the shaft in raised position while the receiving tray is being adjusted.

5. In combination with a tray for containing cards or statements, uprights connected to one side of the tray, a horizontally arranged shaft supported by the uprights, for bodily vertical movement, manually operated means for raising and lowering the shaft, a rod for passing through the cards or statements, arms connected to the rod and means for supporting the arms from the shaft.

ALBERT K. KEKOA.
